(57) **CLAIM**

The ornamental design for an electricity connecting plug, as shown and described.

DESCRIPTION

FIG. 1 is a top, rear, and right-side perspective view of an electricity connecting plug according to the present invention;

FIG. 2 is a front elevational view of the electricity connecting plug shown in FIG. 1;

FIG. 3 is a rear elevational view of the electricity connecting plug shown in FIG. 1;

FIG. 4 is a right-side elevational view of the electricity connecting plug shown in FIG. 1;

FIG. 5 is a left-side elevational view of the electricity connecting plug shown in FIG. 1;

FIG. 6 is a top plan view of the electricity connecting plug shown in FIG. 1; and,

FIG. 7 is a bottom plan view of the electricity connecting plug shown in FIG. 1.

(Continued)

In the drawings, the broken lines show portions of an electricity connecting plug that form no part of the claim.
